UNITED STATES PATENT OFFICE

2,434,572

CORONA SHIELD

Arthur H. Mankin, Philadelphia, Pa., assignor, by
mesne assignments, to Philco Corporation,
Philadelphia, Pa., a corporation of Pennsyl-
vania

Application April 28, 1944, Serial No. 533,221

5 Claims. (CL 174—35)

1

This invention relates to the electrical phenomenon known as corona. More particularly it has reference to the prevention of corona at junctures of high potential conductors.

In electrical apparatus employing high potentials, e. g. radio and television apparatus, it has been found that sharp corners, solder points, and exposed ends of wires at terminal posts or junctures, are conducive to corona, thereby resulting in energy losses and disturbances. While it is possible to reduce these deleterious effects by painstaking elimination of the offending sharp corners and projections, this is not at all satisfactory and at best it is a time-consuming and tedious procedure.

The principal object of the present invention is to provide a simple and efficient means for eliminating corona and its deleterious effects at connections of high potential conductors.

Another object of the invention is the provision of an inexpensive and efficient shield or enclosure for this purpose.

A further object of the invention is to provide a shield which is especially adapted to facilitate such connections.

A still further object of the invention is to provide a novel connector and shield device which simplifies and greatly facilitates the making of the connections.

In the accompanying drawing:

Fig. 1 is a plan view of a shielding device provided in accordance with the present invention, with the cover removed for better illustration; and

Fig. 2 is a vertical sectional view of the device taken along line 2—2 of Fig. 1.

As illustrated in the drawing, the preferred embodiment of the novel shielding device comprises a lower substantially cup-shaped metallic member 2 and a dome-shaped metallic cover 3 adapted to be fitted over the upper edge 4 of member 2, as illustrated in Figure 2. These two members form a hollow shield which encloses the electrical joint with which the device is associated. It is preferred to employ a shield of generally spheroidal shape because curved surfaces are most resistant to corona.

Opposed shallow detents 5 and 6 are provided to firmly secure the shield members together. As may be seen by reference to Figure 1, the shield is preferably oval-shaped to facilitate registry of detents 5 and 6 when assembling cover 3 with cupped member 2. It should be understood, however, that the shield may assume any other ap-

propriate shape, such as that of a sphere, without departing from the invention.

Member 2 has in its bottom wall 7 an aperture 8 through which a screw 9 passes to secure the member to an insulating panel 10. Screw 9 also secures, within and on the bottom wall of member 2, a connection member 11 having a pair of integral upwardly extending terminal prongs 12 and 13. On opposed sides of member 2 adjacent its bottom wall 7, are apertures 14 and 15 formed by punching, or other suitable method, to provide inturned portions 16 and 17 with all sharp edges and corners within said member.

When connecting the high potential conductors 18 and 19, their exposed ends 20 and 21 are passed through apertures 14 and 15 and suitably secured to prongs 12 and 13 as by soldering, indicated at 22. The apertures are preferably of a size to fit snugly about the insulation on the wires. At this time the cover 3 is removed, and since the prongs 12 and 13 project above the cup member 2, the connections may be made very easily. Since the device may be quite small, and may in fact have an overall dimension as small as $\frac{3}{8}$ ", the facilitation of connection is very desirable. After the connections are made, the dome-shaped cover 3 is snapped over edge 4 of member 2 to thus completely enclose all connections and sharp edges. The lower edge of member 3 may be rounded to prevent corona at that point.

It may be seen that prongs 11 and 12 directly contact the floor of lower member 2 to maintain the shield and the conductors 17 and 18 at the same potential. As the curved surface of the spheroidal shield is highly resistant to corona discharge, it will be apparent that the invention has provided an inexpensive and practical device for effectively preventing corona at connection points of high potential conductors, and which enables such connections to be made rapidly without precautionary steps such as rounding or eliminating sharp edges and points.

While a preferred embodiment of the invention has been illustrated and described, it is to be understood that modifications of the structure may be made within the scope of the appended claims.

I claim:

50. 1. A device for connecting two high potential conductors together and for preventing corona at the juncture thereof, comprising a two-part metallic shield, the parts of which are adapted for removable attachment one to the other, and 55 are shaped to constitute a hollow enclosure when

attached together, one of said parts being apertured to receive the ends of the conductors to be connected, and means for electrically connecting the ends of said conductors together and to said one part prior to the attachment of said parts, said shield serving to enclose the electrical juncture of said conductors when said parts are attached together and being maintained at the same electrical potential as the conductors.

2. A device for connecting two high potential conductors together and for preventing corona at the juncture thereof, comprising a hollow metallic shield having provision for receiving the ends of said conductors, a connector element disposed within said shield and serving to interconnect said conductors, and common means for electrically connecting said element to said shield and for securing the shield to an insulating support.

3. An electrical connector and corona shield device, comprising a shallow cup-shaped metallic member having apertures near the bottom thereof to receive the ends of conductors to be connected, a connector element engaging the bottom of said member and having upwardly extending prongs to which the ends of said conductors may be readily connected, and a metallic cover member attachable to said cup-shaped member and forming therewith a hollow shield completely enclosing said connector element and the ends of said conductors, said shield being maintained at the same electrical potential as said conductors

through its engagement with said connector element.

4. A device according to claim 3, including common means for maintaining said connector element in engagement with said cup-shaped member and for securing the latter to an insulating support.

5. A corona-shield electrical joint structure, comprising a two-part hollow metallic shield, the parts of which are adapted for removable attachment to one another, one of said parts being apertured to receive conductors, and a pair of conductors extending into said shield and electrically connected together and to said shield, so that said shield is maintained at the same electrical potential as said conductors.
